Primary Examiner — Susan E Krakower*Assistant Examiner* — Andrew Kerr(74) *Attorney, Agent, or Firm* — Bush Intellectual Property Law; Kenneth M. Bush(57) **CLAIM**

I claim the ornamental design for a grill grid, as shown and described.

DESCRIPTION

FIG. 1 is a bottom perspective view of a grill grid showing my new design;

FIG. 2 is a front elevational view thereof, the rear elevational view being a mirror image of the front elevational view;

FIG. 3 is a right side elevational view thereof, the left side elevational view being a mirror image of the right side elevational view;

FIG. 4 is a top plan view thereof; and,

FIG. 5 is a bottom plan view thereof.

1 Claim, 4 Drawing Sheets(56)
